By his Attorneys:

C. A. Snow & Co.

UNITED STATES PATENT OFFICE.

WILLIAM M. HAZEL, OF GEORGETOWN, DELAWARE.

SASH-HOLDER.

SPECIFICATION forming part of Letters Patent No. 448,339, dated March 17, 1891.

Application filed May 2, 1890. Serial No. 350,364. (No model.)

To all whom it may concern:

Be it known that I, WILLIAM M. HAZEL, a citizen of the United States, residing at Georgetown, in the county of Sussex and State of Delaware, have invented a new and useful 5 Sash-Holder, of which the following is a specification.

The object of my invention is to provide a simple and effective sash-holder—one that will 10 adjust itself and be held in place without the necessity of grooved notched slots, adjustable tables, springs, or other movable devices in order to get proper bearing.

The invention consists in the peculiar formation of the box, and also in the novel construction of the wheel or ball which plays freely in the same, all of which will be more fully set forth in the specification, and shown in the drawings, wherein—

20 Figure 1 represents a section of box and its inner walls on line 1 1 of Fig. 3, with the wheel or ball in position. Fig. 2 represents a similar section on line 2 2, with the wheel or ball in a bearing position in said box. Fig. 3 represents a front view of the sash-holder complete. Fig. 4 represents a side view of box and wheel or ball in bearing position. Figs. 5 and 6 show modified forms of wheel or ball shown in Figs. 1 and 2.

30 Similar letters of reference indicate like parts in the several drawings.

My invention is made of metal, and the box B is constructed with vertical outside walls and grooved inside walls, with its rear wall 35 flattened for a portion of its width and somewhat inclined, as shown in Fig. 4 of the drawings. This box is preferably cast in two pieces and fitted together at the point shown by the lines b in Fig. 3, or it may be cast in one piece, 40 as desired, the result being the same in either case. When so cast in two pieces, the front edge of one member is provided at its upper end with an inwardly-extending tongue t, having a hole h, through which is passed the screw 45 that holds the box in the sash, and the other member has a similar tongue at its lower end.

The wheel or ball A may be made of metal or molded from a composition of hard material, it being only necessary that it shall have 50 no elastic properties. In shape it is spherical at the parts lettered a, which fit in the grooved

inner sides or walls of the box B, as shown in dotted lines in Fig. 3 and in full lines in Figs. 1 and 2, and it is provided at the points lettered a' a' with a raised, rounded, flattened, or angular-faced ring, which rests against the rear wall of the box B and against the edge of the window-frame if the box be seated in the sash, or against the sash if conversely placed. This ring is comparatively narrow— 60 i. e., narrower than the edge of the sash or the groove in the frame in which the sash moves—as will be seen from the drawings, and hence when a considerable strain is brought to bear upon the ball it will sink into or indent the sash or frame.

In operation, the parts being properly placed in a window, the wheel or ball A rolls freely up and down in the box B when moving the window up or down, and when pressure is 70 taken off the sash the wheel or ball A drops readily into a bearing position against edge of sash. The wheel or ball A being made slightly raised at the points a' a', it will be observed, is a great improvement, because in 75 use, being narrower than the edge of the sash, it will gradually embed itself in said sash or frame, and thus increase its holding qualities, as well as positively prevent the rattling of 80 the window.

I show in Figs. 5 and 6 modified forms of my invention which may be employed with the box without departing from the spirit of this invention, as the results are identical.

It will be observed that my invention by 85 reason of the grooved inner side walls of box and novel construction of wheel or ball gives such a stubborn resistance all around the grooved walls and the ball as to compel the sash to remain in position desired when the 90 wheel or ball is at rest against the indented edge of sash, thus forming a very strong attachment and one that cannot get out of order or become detached. At the same time it adjusts itself from time to time as the window may shrink or swell. These features are 95 decided improvements, which will be readily appreciated by builders, because when once set the job is complete, as no future adjustment becomes necessary.

Heretofore much difficulty has been experienced in devices of this character, owing to 100

the crushing or breaking of the box if the sash were forced strongly downward when held by the ball. This was owing to the fact that where spherical balls were used they bore
5 at but one point against the box and where the balls were cylindrical they bore only across a single line. The box being generally of light casting was easily crushed if too great pressure were brought to bear thereon; but where
10 the spherical faces $a a$ travel in grooves in the side walls and the raised faces a' bear squarely against the rear wall of the box a double, or rather triple, bearing or resistance is provided in the box, the spherical faces
15 wedging the sides of the box outwardly and the flat face driving its rear wall backward. The strain resulting is therefore distributed over a considerable part of the box and exerted in three directions, and the result is
20 that the box is much less likely to be broken or crushed.

Having fully described my invention and its advantages, what I claim as new and useful, and desire to secure by Letters Patent, is—

25

In a sash-fastener, the combination, with the box having grooved side walls and an inclined rear wall, of the ball having spherical sides fitting loosely in said grooved side walls, and a ring around said ball raised above the 30 line of the spherical sides, said ring standing against said rear wall and extending beyond the front of the box when in its operative position, substantially as described.

In testimony that I claim the foregoing as 35 my own I have hereto affixed my signature in presence of two witnesses.

WILLIAM M. HAZEL.
